Primary Examiner — Marianne Pandozzi*Assistant Examiner* — Jae Liang(74) *Attorney, Agent, or Firm* — Polsinelli PC(57) **CLAIM**

The ornamental design for a lid and bottle combination, as shown and described.

DESCRIPTION

FIG. 1 is a perspective view of a lid and bottle combination showing our new design;

FIG. 2 is a front view of the lid and bottle combination;

FIG. 3 is a rear view of the lid and bottle combination;

FIG. 4 is a left side view of the lid and bottle combination;

FIG. 5 is a right side view of the lid and bottle combination;

FIG. 6 is a top view of the lid and bottle combination; and,

FIG. 7 is a bottom view of the lid and bottle combination. The broken lines in the drawing depict portions of the lid and bottle combination that form no part of the claimed design.
